APPARATUS FOR DISCHARGING THE CONTENTS OF CONTAINERS

Max Jegge, Menziken, Switzerland, assignor to Ciba Limited, Basel, Switzerland

Filed Oct. 31, 1958, Ser. No. 771,044

Claims priority, application Switzerland Nov. 1, 1957

2 Claims. (Cl. 214—315)

This invention relates to apparatus for discharging the contents of containers, especially for use on fork lift trucks.

Apparatus for discharging the contents of cask or like containers for transport or storage, and which is associated with transporting vehicles known as fork lift trucks, is known in which the cask, held, for example, between two clamps, is tilted about an axis of rotation approximately coincident with the centre of the cask in order to discharge its contents, after removing a closure from an opening at the top of the cask. The use of such an apparatus for discharging liquid, pasty or pulverulent materials into receivers that usually have a relatively narrow charging opening has the disadvantage that the cask being discharged must, in addition to being tilted by rotation, be moved laterally in order to maintain the portion of the opening of the cask, from which the contents are being charged, because only in this way is satisfactory charging without spilling ensured.

An object of the present invention is to overcome the aforesaid disadvantage. Accordingly, the invention provides a method for discharging the contents of containers, especially for use on fork lift trucks, which comprises means for holding a container and tilting it about an axis that at least approximately coincides with the portion of the opening of the container from which the contents are discharged.

The invention also provides a simple and efficient means for performing the aforesaid tilting movement.

An example of an apparatus constructed in accordance with the invention is illustrated in the accompanying drawings, in which

Fig. 1 shows in side elevation a fork lift truck provided with the apparatus for discharging the contents of a container,

Fig. 2 shows a front elevation of the fork lift truck and apparatus shown in Fig. 1,

Fig. 3 shows diagrammatically in elevation the driving mechanism for tilting the container, and

Fig. 4 shows the means for holding the container.

In Fig. 1 is shown a fork lift truck provided with an apparatus constructed in accordance with the invention. The means for driving the truck is arranged within a truck housing 1 which runs on three or four wheels 2. Above the housing 1 is a seat 3 for the operator and a steering wheel 4 and the usual operating levers 5 etc. At the front of the truck is a standard 7 upon which a travelling carriage 8 is hydraulically movable at least in a vertical direction. Normally there are provided on the travelling carriage of such a fork lift truck forks (not shown) to receive goods to be conveyed. Instead of these forks, there is provided on the carriage 8 an apparatus constructed in accordance with the invention, which includes a plate-like member 10 connected to the carriage 8 and a plate-like member 11 is provided at its front side with laterally adjustable holding clamps 12 for holding a cask 13 as shown.

Fig. 2 shows a front elevation of the truck and tilting

2

apparatus. In front of the truck housing 1 is the standard 7 on which the member 10 is fixed at about half the height of the standard. On the member 10 is mounted the member 11 which is rotatable about an axis 15 and is shown tilted at nearly 90°. The member 11 has fixed thereto four clamps 12 for holding the cask.

Rotation of the member 11 relatively to the member 10 serves for discharging the contents of the cask 13, and is effected by means of a driving mechanism mounted on the member 11 in the apparatus illustrated. In accordance with the invention the axis of rotation 15 is at least approximately coincident with the portion of the opening of the cask 13, from which the contents are discharged. In this manner it is ensured that during the gradual emptying of the cask the liquid contents thereof are continuously discharged from approximately the same position. For the purpose of illustration the liquid is shown as being charged into the opening 18 of a reaction vessel 19.

Advantageously, the axis of rotation is disposed laterally of the centre of the truck, so that during transport the cask is approximately on the centre line of the truck, that is to say, the cask does not project on either side of the truck. Furthermore, the cask can be brought from one side very close to the charging opening of the vessel to be charged.

The advantages of such an arrangement are easy to see. Due to the fact that the tilting axis during discharging is substantially coincident with the discharging portion of

the opening of the cask, the contents are discharged throughout from practically the same position until the cask is completely empty, without requiring any special attention from the operator or necessitating any further movement of the truck or the apparatus. In the case of

the known apparatus hereinbefore described, in which the axis of rotation approximately coincides with the centre of the cask, the point of discharge moves laterally during the pouring operation to an extent which depends on the inclination of the cask. Thus, when the contents are to be discharged from such an apparatus into the charging opening of another vessel, it is necessary to carry out a lateral movement in addition to tilting the cask. This necessitates an additional difficult manipulation of the apparatus during discharging, and, if this is done by moving the truck itself, cannot be carried out in a restricted space. The location of the tilting axis laterally of the centre of the truck also has the advantage that the operator, while sitting on the seat 3, can look past one side of the standard 7 and observe the entire charging operation.

Fig. 3 shows the driving mechanism which is mounted on the rotatable member 11 for tipping the cask. In order to protect the driving mechanism from dirt and damage it is enclosed within a casing. As shown in Fig. 3 the front side of the casing has been omitted to reveal the driving mechanism. A wheel 20 projects into the casing and is fixed to the non-rotatable member 10. This wheel serves as a non-rotatable take-up wheel for a device described below. A chain or cable 21 passes round the wheel 20 and is fixed to the wheel, for example, by means of an eye 22 and a pin 23. One end portion of the chain 21 passes over a pulley 24 and is fixed at its end to the member 11 by means of a lug 26. The other end portion of the chain 21 passes over the guide roll 28 and a pulley 25, and is fixed at its end to the member 11 by means of a lug 29. The pulleys 24 and 25 are connected together by means of a link 30 which is connected to the working piston of a double acting hydraulic working cylinder 31.

When the liquid is supplied to one or other side of the piston in the cylinder 31 the piston and the link 30 move to the right or left. In this manner the chain lengths extending between the wheel 20 and the lug 29 and be-

tween the wheel 20 and the lug 26 change in opposite senses. Since the take-up wheel is fixed, the aforesaid change in lengths causes the whole assembly including the member 11 to rotate about the axis 15 of the wheel 20 and thus perform the tilting movement described above. The clamps 12 on the lower portion of the member 11 are also operated hydraulically. In the apparatus shown the driving mechanism for causing the tilting action is mounted on the member 11 carrying the cask. It will be understood, however, that the driving mechanism may be provided on the stationary member 10. However, the arrangement of the driving mechanism on the member carrying the cask, as shown, saves space and also renders the mechanism more easily accessible, and so simplifies and cheapens the construction and operation of the apparatus.

The guide roll 28 is so arranged in one portion of the chain relative to the take-up wheel 20 and the two pulleys 24 and 25 that all four of the portions of the chain extending from the pulleys are parallel with one another. The result of this is that the total length of the chain between the two lugs 29 and 26 remains constant irrespective of the movement of the pulleys, whereby a positive connection between the plate-like members is achieved. Accordingly, there is no undesired lost motion during the tilting of the cask in an upward or downward direction. The guide roll 28 may be replaced by a resilient connection between the chain and one or both of the lugs 26 and 29. In this case, however, the positive connection between the two plate-like members becomes a resilient connection, which is especially undesirable when heavy containers are to be handled.

It will be understood that the invention is not limited to the construction shown in the drawings, and that any other driving mechanism may be used for tilting the member 11 relatively to the member 10. For example, instead of the mechanism comprising the chain and pulleys, there may be used a toothed rod operated by the hydraulic cylinder, which rod engages teeth on the take-up wheel. However, as compared with such an arrangement, the mechanism shown in Fig. 3 has the advantage that, owing to the block-and-tackle type of action of the pulleys 24 and 25 the stroke of the piston of the cylinder 31 is half of that required by the toothed rod construction, and that no outwardly projecting parts, such as toothed rods or pistons, are required. The tipping action can also be produced by means of a worm drive operated by an electric motor or internal combustion engine. However, having regard to the greater compactness of the hydraulic drive for a given power output, the mechanism illustrated in Fig. 3 occupies considerably less space.

In general the clamps 12 for holding the cask are movable on both sides of the cask so that the latter can always be held in a central position with respect to the truck. This has the advantage of affording maximum stability to the truck during its travel. It is, however, more advantageous so to construct the mechanism oper-

ating the clamps that the clamps on each side can be moved independently of each other in a lateral direction for gripping the container, so that containers of different sizes can be held and also held in such a position that the discharging portion of the opening of the cask coincides with the tilting axis 15. This is shown diagrammatically in Fig. 4.

For example, when a larger cask 40 is to be discharged it is held on both sides by means of the clamps 41 and 42, and the cask is positioned approximately centrally with respect to the truck. The discharging portion 43 of the opening 44 of the cask coincides with the tilting axis 15. When a smaller cask 46, shown in broken lines, is to be discharged, the clamps 42 are left in their extreme position and the cask 46 is held in position merely by moving the clamps 41 to the position shown in broken lines. In this manner the discharging portion 47 of the opening of the cask 46 likewise coincides with the tilting axis 15.

20 What is claimed is:

1. Apparatus for discharging the contents of containers, especially for use with fork lift trucks, which comprises a main frame, holding means on said main frame for a container with an opening having a discharge lip, elevating means on said main frame for effecting a linear vertical movement of the holding means relative to the main frame, tilting means on said main frame for effecting a tilting movement of said holding means, said tilting means comprising two plate-like members one of which is rotatable relatively to the other and carries the container holding means and a driving mechanism comprising a take-up wheel non-rotatably fixed to one of the plate-like members and, mounted on the other plate-like member, a double-acting working cylinder, a pair of pulleys connected to the piston of the cylinder, and a chain or cable which passes round and is fixed between its ends to the take-up wheel, and of which one of the two end portions passes round one of the said pulleys and the other end portion round the other pulley and then each end is fixed to the last mentioned plate-like member, the holding means being positioned relative to the tilting axis of said tilting means so that the tilting axis passes through a point at which the discharge lip of the container is positioned when it is held in said holding means.

2. Apparatus as claimed in claim 1, wherein one end portion of the chain or cable also passes round a guide roll, and the take-up wheel, guide roll and pulleys are so disposed relatively to one another that all the portions of the chain or cable extending from the two pulleys are parallel with one another.
